DISHWASHER

Ralph E. Marbury, Wilkinsburg, Pa., assignor to
Westinghouse Electric & Manufacturing Com-
pany, a corporation of Pennsylvania

Application November 11, 1931, Serial No. 574,253

4 Claims. (Cl. 141—9)

My invention relates to household appliances and more particularly to dish washers.

An object of my invention is to provide a relatively simple and highly efficient dish washer.

5 Another object of my invention is to provide a dish washer that shall have a minimum number of operating parts.

Another object of my invention is to provide a dish washer that shall be self cleansing and be 10 easy to maintain in sanitary condition at all times.

Another object of my invention is to provide a dish washer that shall embody means for preventing water from the tub entering a motor de- 15 pending therefrom.

In practicing my invention I provide a container or tub having a motor depending therefrom and supported thereby, and a motor shaft extending into the tub and engageable by a re- 20 movable impeller unit. A water inlet pipe enters the container near its upper edge and a rotatable spray pipe, supported on the inside of a hinged cover, engages the inlet pipe when the cover is closed.

25 In the drawings:

Figure 1 is a view in front elevation of a sink with which is associated a dish washer embodying my invention.

Fig. 2 is a view in vertical section therethrough 30 taken on the line II—II of Fig. 1.

Fig. 3 is an exploded view, partly in section and partly in side elevation, of a part of a dish washer embodying my invention and showing more particularly a rotatable spray pipe.

35 Fig. 4 is a fragmentary view, partly in section and partly in side elevation, of a water inlet pipe,

Fig. 5 is a partial view, in front elevation, of a rotatable spray pipe.

Fig. 6 is a perspective view of a fluid-guide and 40 tray-supporting member, and

Fig. 7 is a view, mainly in vertical section, through the motor and impeller unit.

I have illustrated my improved dish washer as 45 constituting an integral part of a sink structure shown generally at 11 in Fig. 1 of the drawings.

This sink structure is of the usual construction now provided in many homes and includes a back wall 12 and the usual depressed sink 13 with a front apron 14, all of the usual or standard kind. A tub or container 16 may constitute an 50 integral part of the structure 11, and, while I have elected to illustrate and describe the parts or elements more particularly constituting my invention as applied to a stationary structure, my invention is not limited thereto, but the container

16 and the other parts associated therewith may be made in the form of a movable device, and is well known to those skilled in this particular art.

A drain pipe 17 is provided for the sink portion 13 and water inlet pipes controlled by a usual fixture 18 may also be provided. The drain 17 is connected to an outlet pipe 19 and the tub or container 16 is provided with a suitable outlet pipe 21 which is opened or closed by an actuating handle 22 or by any suitable similar means effective 5 for the desired purpose. The outlet 21 is connected to pipe 19 by suitable means designated generally by the numeral 23 in Fig. 1 of the drawings.

The tub 16 has a water inlet pipe 26 entering 15 the same near the upper rear edge thereof immediately below a hinged cover 27, which is pivotally supported by a plurality of suitable hinges 28 secured to the back wall 12.

A rotatable spray pipe assembly is illustrated 20 more particularly in Figs. 3 to 5 inclusive of the drawings and includes a fixed tubular socket 31 which may be located substantially centrally of the cover 27 and which has one end of a radially-extending spray inlet pipe 32 connected thereto, 25 the other end of the pipe 32 fitting tightly into a block 33 held against the under surface of the cover 27 by any suitable means not shown in the drawings. The block 33 has an opening there- 30 through, indicated by the broken lines to provide a conduit 34 of substantially S-shape, one end of which registers with one end of the spray inlet pipe 32 and the other end of which is adapted to fit tightly over the inwardly projecting end 36 of inlet pipe 26 when the cover is closed so that 35 water flowing through pipe 26 may flow also through conduit 34 and into pipe 32. The opening in pipe 26 extends downwardly at the inner end of portion 36, as is indicated at 37 in Fig. 4 of the drawings, so that if it is desired to admit 40 water into the tub 16 at a time when the cover 27 is in its open position, the water will flow downwardly, thereby preventing splashing thereof on an operator who may be standing in front of the tub 16.

45 A rotatable spray structure mounted on the socket 31 includes a top hub 38 having a central opening 39 therein of such size as to fit over the socket 31. A pair of radially-extending tubular wings or conduits 41 and 42 have their inner ends fitting into the hub 38 which is provided with radially-extending openings 43 therein to permit 50 water to flow into the radial wings 41 and 42. These tubular members are closed at their outer ends and are severally provided with a number 55

of relatively small openings 44 which are located at opposite sides of the two members so that water flowing out of these openings and, therefore, substantially tangentially to the axis of the tub, will cause this hub to rotate.

Means for holding the hub in its proper operative position on the socket 31 may include a holding nut or stop 46 which is also of tubular shape and provided with an enlarged flange interfitting with the hub 38, and an upper extension 47 having screw-threads thereon, which engage internal screw-threads in the lower part of the tubular socket 31. A bottom spray pipe 48 has its upper end in tight engagement with a bottom piece 49 which is of conical tubular shape, the upper enlarged end portion having inner screw-threads fitting onto the lower portion 51 of hub 38. The intermediate part of member 49 is provided with a plurality of radially-extending relatively small openings 52 through which water may flow. Spray pipe 48 is provided with a plurality of circumferentially distributed small water outlet openings 53 and more particularly with two slots 54 and 55 at its bottom end, which slots may be of substantially 90° in arcuate extent and which are made wide enough so that a substantial quantity of water may be admitted therethrough. It may be here pointed out that I consider the provision of these arcuate slots in the end of the spray pipe 48, which end is of semi-spherical shape, as an important element in my improved dish washer, as the water emitted therefrom is in the shape of a flat spray of fan shape. The width of the slots 54 and 55 is such that, as hereinbefore stated, a considerable quantity of water may flow therethrough, which operation together with the rotating motion of the pipe will be particularly effective in rinsing dishes after they have been cleansed of adhering matter.

Referring to Fig. 2 of the drawings, I have illustrated a wire basket 61 of open construction in which dishes, such as plates 62, may be stood on edge with their soiled inner surfaces facing the axis of the tub 16. I have found it preferable to place the flat tableware, such as plates, in the bottom of the wire basket 61 and cups 63 and tumblers 64 in an upper portion of container 61, substantially as indicated in Fig. 2 of the drawings. The inside of the cups and tumblers should also point inwardly in order that water from the openings 52 and 53 in the rotatable sprayer may be forced into the inside of these dishes.

Referring now to Fig. 7 of the drawings, it may be noted that the tub 16 is provided with an opening 71 in the bottom wall thereof, in which opening there is located an outer bushing 72 which has an integral enlarged flange 73 at its upper end resting upon a suitable gasket 74 in order to cooperate with other elements to provide a watertight closure for the bottom of the tub. A driving-motor structure includes a motor housing 76 having a bearing bracket 77 either integral therewith or secured thereto in a manner well known in the art. The housing 76 has located therein the usual stator structure of a motor (not shown in the drawings) and a rotor structure (not specifically shown in the drawings) is indicated more particularly by a rotor shaft 78, the upper end of which is maintained in proper operative position within the bearing bracket 77 by a ball bearing 79 located in a bearing flange 81 of usual construction. I have illustrated certain details of the shaft of the upper bearing structure for illustrative purposes.

poses, but my invention is not limited to these specific details, as any other elements operative for the same purpose may be utilized.

The upper end 82 of bearing bracket 77 is made of lesser diameter and is provided with internal screw threads so that the motor and the bearing bracket may be suspended from the bushing 72 by being screwed thereon, this screw-threaded engagement being made tight enough to compress the upper annular gasket 74 and a lower outer gasket 83 to ensure a fluid-tight joint and closure of the opening 71. I may here state that while the upper portion 82 directly engaging the bushing 72 is illustrated as being integral with the bearing bracket 77, my invention is not limited to this particular construction and I may utilize an upper member directly engaging the bushing 72, which is made separate from the part of the bearing bracket directly engaging the housing 76 as may be found necessary or desirable for construction or assembly purposes. The lower portion of the tubular bushing 72 has an annular recess 84 therein by the provision of an inner annular flange 86.

An inner bearing sleeve 81 surrounds the upper portion 92 of rotor shaft 78, the lower end portion 93 thereof fitting within the annulus 86, hereinbefore described, and being adapted to compress a fluid tight packing 94 inside of the annulus 86, which, as shown in Fig. 7 of the drawings, is provided with a lower annular portion 96 to retain the packing 94 in its proper operative position. The upper end portion of member 91 is provided with external screw threads fitting and screwing into internal threads 33 in bushing 72, whereby the packing 94 may be tightly compressed.

The upper end of member 91 is provided with an annular recess 97 in which is located an upper packing 98 which is held in place and compressed by an upper sleeve 99 which is, in turn, held within the opening 97 by a nut 101, the lower end of which has screw-threaded engagement with the upper end portion of member 91.

It is very desirable, if not necessary, that fluid which may be located in the tub 16, be prevented from entering the motor structure depending therefrom, which fluid might find its way along the external periphery of shaft 92. In order to prevent this, I provide two annular recesses 102 and 103 in member 91 intermediate its ends and, therefore, intermediate the two packings 94 and 98. A plurality of openings 104 in member 91 extend downwardly and slightly outwardly from the annular recesses 102 and 103. Extended operation of the device has shown that any water flowing downwardly along the shaft 92 past the sleeve 99 and through the packing 98 will be thrown radially outwardly when it reaches the annular recesses 102 and 103, and, as the openings 104 communicate with the outer portions of these recesses, and particularly the lower portions thereof, any fluid thus trapped will flow downwardly into the recess 84 from which it may be conducted away from the motor structure by a pipe 106. It may be noted by reference to Fig. 1 of the drawings that this pipe is connected by suitable intermediate members to the outlet pipe 19.

A removable impeller unit includes a conical sleeve 111 of tubular shape, the lower opening 112 therein being of such internal diameter as to fit snugly over the nut 101 to be centered thereby. The upper reduced portion 113 has a bearing sleeve 114 therein in which is located a rotatable

- stub shaft 116 provided with a groove 117 at its lower end into which a tongue 117a on the upper end of shaft 92 may fit to effect a driving connection therebetween.
- 5 An impeller structure 118 has screw-threaded engagement with the upper end of shaft 116 which projects beyond the thrust sleeve bearing 114 and any suitable or desired number of vanes or blades 119 may be provided. It may be noted 10 that the impeller structure including more particularly the impeller 118 and the supporting sleeve 111, may be easily and quickly removed from operative engagement with the upwardly projecting end portion of shaft 92 and its 15 rounding bearing structure and that so long as it is in operative engagement therewith and the impeller is being driven by the motor, the reactive thrust on the vanes 119 will maintain such operative driving engagement.
- 20 Referring to Figs. 2 and 6 of the drawings, 121 indicates a fluid-guiding and tray supporting member, including a tubular shroud 122 surrounding the impeller blades 118, a substantially flat annular portion 123 at the bottom of shroud 25 122 and a plurality of flat radially-extending guide and supporting portions 124 whose upper edges are secured to the lower surface of annulus 123 and whose lower edges conform to the surface of the sleeve 111. This provides not only 30 a support for the basket 61, but also ensures that the water actuated by the impeller will move in a proper path from the outside of the tub and between the conical surface of member 111 and the annulus 123, the thin vertical members 124 35 preventing swirling of the water circumferentially of the axis of the impeller.
- If it is desired to operate the dish washer, the larger plates and similar tableware will be placed in positions shown in Fig. 2 of the drawings, 40 standing on edge and preferably having the upper edges thereof located farther radially outwardly than the lower edges thereof, the tumblers and silverware being located at the top of the basket 61. Upon closure of the cover 27, hot 45 water may be turned on to enter the pipe 26 from which it will flow through conduit 34 into the fixed pipe 32 and outwardly through the spray structure shown more particularly in Figs. 3 to 5 inclusive of the drawings, and, I prefer to permit 50 such a quantity of water to enter the tub as to bring the fluid level thereof to substantially the broken lines indicated by 131 in Fig. 2 of the drawings. The motor may be energized coincident with the admission of water to the tub, and, 55 by actual observation, I have determined that the water thrown upwardly by the impeller 118 when there is but a small quantity of water in the tub barely sufficient to be agitated or moved by the blades, will be thrown substantially vertically upwardly inside of the tubular member 122, the general shape of the path of the water drops or particles being that of a spiral whose initial travel is vertically upwardly and then spirally outwardly.
- 60 65 As the quantity of water in the tub increases, the spiral path changes, as does also the vertically-upward path, the former becoming more and more radial and the latter becoming more and more angularly radially outwardly. This will be especially the case when the level of the water is substantially that indicated by the broken line 131, at which time there will be an efficient surging action, as well as a highly efficient circulation of the water, the surging action 70 being sufficient to remove soil adhering to the plates by a scouring action while the circulation of the water presents fresh water, so to speak, to assist in softening the adhering soil which may then be more easily removed by the surging action of the water.
- If an excessive quantity of water be located in the tub, as for instance if the water level is at the broken line 132 of Fig. 2, the surging action will be greatly decreased and the water will be merely circulated, but with relatively little dynamic force therein. Because of the path of the circulating water being radially upwardly and outwardly, an efficient cleansing action on the entire surfaces of plates 62 and other dishes is effected and it is not essential that a minimum number only of such dishes be placed in the basket as the circulation of the water will effect a cleansing of all of the dishes within a relatively short time, it being understood, of course, that suitable soap or soap powders may be provided to assist in cutting and removing any greasy soil.
- 10 15 20 25 30 35 40 45 50 55 60 65 70 75
- After the dishes located within the tub 16 have been thoroughly cleansed, the drain may be opened and the water permitted to flow out of the tub. Then the dishes are rinsed by admitting water to the inlet pipe 26 which will then flow out of the spray structure hereinbefore described, the reactive effect of the water flowing through the openings 44 in pipes 41 and 42 causing a rotation of the spray structure. A relatively large volume of water will flow out of the spray pipe 48 through the openings 54 and 55, this spray being of fan shape and rotating so that an efficient rinsing action of the hot water on the dishes will be obtained, while at the same time water flowing outwardly through the openings 52 will effect a rinsing action of tableware located in the upper part of the wire container 61. It is not necessary that the drain from the tub be closed during the rinsing action, thereby permitting an effective flushing action of the entire interior of the machine.
- Extended experiments with a bearing structure of the kind shown in Fig. 7 of the drawings has indicated that there is little or no leakage of water flowing downwardly along shaft 92 into the motor structure, but that there is an appreciable drainage out through pipe 106, thus showing that the device particularly embodying my bearing structure is highly efficient in precluding entrance of water into the motor structure.
- The device embodying my invention thus provides a relatively simple and highly efficient structure for, first, washing and then rinsing dishes which may be placed in a container, the structure embodying relatively few and simple parts highly efficient for the desired purpose.
- Various modifications may be made in my invention without departing from the spirit and scope thereof, and I desire, therefore, that only such limitations shall be placed thereon as are imposed by the prior art or are set forth in the appended claims.
- I claim as my invention:
1. In a washer including a container having an opening in the bottom wall thereof, a bushing structure in the opening and a motor-driven shaft extending upwardly through the bushing structure, and an impeller structure supported on the bottom wall of the container and including a supporting conical sleeve interfitting with bushing structure, an impeller and a driving shaft therefor supported by said sleeve, said shaft having a loose driving engagement with the motor-driven shaft.

2. In a washer including a container having an opening in a bottom wall and a motor driven shaft projecting upwardly through said opening, a bearing structure for the shaft supported by 5 and secured to said bottom wall, a conical sleeve resting on the bottom wall, surrounding the bearing structure and having a bearing sleeve in its upper end, an impeller resting on the bearing sleeve and an impeller shaft extending through 10 the bearing sleeve in the upper end of the conical sleeve, said impeller shaft having a tongue and slot connection with the motor driven shaft.
3. A washer including a tub, an impeller in the tub adapted to circulate fluid therein, driving means for the impeller, an annular sleeve of conical shape resting on the bottom wall of 15 the tub and supporting the impeller, a material-receiving basket around and above the impeller, and a fluid-guiding and basket-supporting mem-

ber extending around and below the impeller, said member comprising a tubular fluid-guiding shroud surrounding the impeller and a plurality of vertical radially-extending fluid-guiding blades resting on the annular sleeve. 5

4. A washer including a tub having a bottom wall having an opening therein, a bushing in said opening, a bearing sleeve assembly interfitting with and supported by said bushing, a rotatable shaft extending upwardly through said bearing sleeve assembly, a sleeve element resting on the bottom wall of the tub extending above the bearing sleeve assembly and operatively centered thereby relatively to the shaft, an impeller structure supported by the sleeve element and including an impeller shaft extending into the sleeve element and having a tongue and slot connection with the rotatable shaft. 10 15

RALPH E. MARBURY.
